US0D1072923S

(12) **United States Design Patent** (10) **Patent No.:** **US D1,072,923 S**
(45) **Date of Patent:** **** Apr. 29, 2025**

(54) **GLASSES**

(71) Applicant: **Xiamen Xutu Optical Glasses Co., Ltd.**, Fujian (CN)

(72) Inventor: **Jiqiang Gong**, Fujian (CN)

(73) Assignee: **Xiamen Xutu Optical Glasses Co., Ltd.**, Xiamen (CN)

(**) Term: **15 Years**

(21) Appl. No.: **29/952,135**

(22) Filed: **Jul. 14, 2024**

(30) **Foreign Application Priority Data**

Jan. 15, 2024 (CN) 202430026423.5

(51) **LOC (15) Cl.** **16-06**

(52) **U.S. Cl.**

USPC **D16/326**

(58) **Field of Classification Search**

USPC D14/372; D16/100, 101, 300-342; D29/105-110
